UNITED STATES PATENT OFFICE.

STEN E. HOFFMAN, OF GARY, INDIANA.

CHECK PROTECTOR.

Application filed April 19, 1924. Serial No. 707,559.

My invention relates broadly to check protectors and more particularly to a check protector adapted to be carried in the pocket of an individual, or attached to a check book holder where it may be conveniently accessible for use as the checks are filled in.

A further object of my invention is to provide a device of the above type which will be compact, simple and inexpensive to manufacture. The arrangement of the parts of the device provides a simple construction which is exceedingly efficient in its operation, in that an accurate impression on the check may be made.

In order to apprise those skilled in the art how to construct and practice my invention, I shall now describe an embodiment thereof in connection with the accompanying drawings which form a part hereof.

In the drawings—

Figure 1 is a perspective view of a pocket check protector embodying my invention;

Fig. 2 is a longitudinal sectional view of this device;

Fig. 3 is a transverse view taken on line 3—3 of Fig. 2; and

Fig. 4 is a top plan view of my device, but illustrating the cover and certain other parts broken away to show the manner in which the type bars are disposed in the casing.

The pocket check protector which is disclosed in the drawings, and in which I have chosen to illustrate a preferred embodiment

of my invention, comprises a casing 2 which may consist of a sheet metal stamping provided with its longitudinal edges turned up to form sides 3 and 4, and with one end closed by the wall 5. To the end wall 5, a cover 6 is pivoted, which cover is adapted to close upon the top face of casing 2. Casing 2 is preferably elongated so that it will be flat and thin to permit it to be readily slipped into the pocket of the user, or fitted to the usual check book employed to carry blank checks.

Upon the back wall or base 7 of casing 2, a plurality of type bars 9 are adapted to be disposed and to have relative movement so that when a selection of characters is to be made, the operator may make the same by pulling the respective type bars forwardly by means of upturned ends 10 on the type bars 9. When these selected characters register with the sight opening 11 provided in a superimposed plate 12 within casing 2, an in-

king pad 13 is advanced forwardly over these selected characters, which inking pad 13 may then be moved downwardly to engage the surface of these characters. Inking pad 13 is also preferably superimposed over the type bars 9, and is supported at the rear end by a roller 15 which rests upon the type bars 9 and rides over the same when the inking pad is moved into and out of the casing 2. Any suitable means may be provided to advance the inking pad 13 forwardly or towards the open end 17 of the casing 2. I have illustrated in the drawing, a U-shaped bar 18, which normally extends a short distance without the open end 17 of casing 2 so that it may be readily gripped by the operator. This U-shaped bar 18 extends rearwardly in the casing and is arranged to suitably carry the inking pad 13 and the roller 15 in journaled relation. I wish it to be understood that any form of inking pad or construction for supplying ink to the characters on the type bars 9 may be employed and consequently I do not desire to be limited to the disclosure herein.

Plate 12 serves to protect the inking pad and at the same time it serves as a cover for casing 2 when the outside cover 6 is in open position. Moreover, it provides a finished appearance for the pocket check protector and furnishes a sight opening, by means of which the operator can ascertain when the type bars have been properly set for a desired selection of characters.

Any suitable means may be provided to retain the type bars in their selected position but in the drawings I prefer to illustrate upstanding beads 20 formed in the back wall or base 7 of casing 2. These beads 20 are adapted to register in corresponding depressions 21 fitted in the underside of the various type bars 9. I have found it preferable to provide a depression 21 under each of the different characters on the type bars 9, so that the operator can ascertain whether the type bars will temporarily hold themselves in selected position.

The blank check is inserted in the device crosswise at the open end 17. The cover 6 is then moved to closed position against the casing 2 which causes a pad 22 to enter the sight opening 11 and to force the check into engagement with the type bars 9. It is desirable to provide sight opening 11 of such a size that a limited portion of the check will enter the same so that no mistake will

be made in having the proper impression made upon the check. I do not intend to be limited to the number of type bars employed, nor the nature of the characters upon the type bars. The word "pay" may be formed upon one of the type bars, or, if so desired, the name of the individual owning the check protector may be used instead, as is now customary in larger check protectors.

Without further elaboration, the foregoing will so fully explain the gist of my invention, that others may, by applying current knowledge, readily adapt the same for use under varying conditions of service, without eliminating certain features which may properly be said to constitute the essential items of novelty involved, which items are intended to be defined and secured to me by the following claims.

I claim—

1. A pocket check protector comprising a casing provided with a cover adapted to receive a check between the casing and cover

and to produce an impression upon the check by the closing movement of the cover, a plurality of movable type bars slidable along the base of said casing, a slidible inking pad superimposed above said type bars but normally remaining out of contact with the same, means for moving said type bars to permit a selection of characters for an impression upon said check, and means for moving said inking pad forwardly and then downwardly into engagement with said selection of characters.

2. A pocket check protector comprising a substantially closed casing having one end open, a plurality of type bars disposed in said casing and accessible at said opening, a U shaped bar extending into said casing, an inking pad movable by said bar, and a movable roller at the inner end of said bar for normally supporting said inking pad out of contact with said type bars.

In witness whereof, I have hereunto subscribed my name.

STEN E. HOFFMAN.
